UNITED STATES PATENT OFFICE

104,191

DESIGN FOR A SHOE HEEL

John Thomas Kershaw, Bradford, Mass., assignor
to New England Wood Heel Company, Haver-
hill, Mass., a corporation of Massachusetts

Application October 16, 1935, Serial No. 59,019

Term of patent 7 years

To all whom it may concern:

Be it known that I, John Thomas Kershaw, a citizen of the United States and a resident of Bradford, county of Essex and Commonwealth of Massachusetts, have invented a new, original, and ornamental Design for a Shoe Heel, of which the following is a specification, reference being had to the accompanying drawing, forming part thereof, in which Fig. 1 is a side elevation of a shoe heel embodying the present invention with

the novel top-lift thereof shown attached to the heel illustrated in dot-and-dash lines; and Fig. 2 is a rear elevation of the same.

The dominating features of my design reside in the parts shown in full lines.

I claim:

The ornamental design for a shoe heel, substantially as shown and described.

JOHN THOMAS KERSHAW.
